UNITED STATES PATENT OFFICE.

WILLIAM J. JEFFRIES, OF OREGON CITY, OREGON.

BOILER-FEEDER.

No. 874,080.

Specification of Letters Patent.

Patented Dec. 17, 1907.

Application filed May 28, 1907. Serial No. 376,204.

To all whom it may concern:

Be it known that I, WILLIAM J. JEFFRIES, citizen of the United States, residing at Oregon City, in the county of Clackamas and State of Oregon, have invented certain new and useful Improvements in Boiler-Feeders, of which the following is a specification.

The present invention relates to a novel device for regulating the supply of feed water to a steam boiler whereby the water within the boiler is prevented from falling below a certain level or rising above a predetermined elevation.

The object of the invention is to provide a feed water regulating mechanism which is entirely automatic in its operation and which at the same time is simple and inexpensive in its construction.

To this end the invention resides principally in the provision of a boiler feeder comprising a water column in communication with the boiler, a pair of steam pipes leading from the water column to a cylinder, the admission of steam to the said pipes being governed by the level of the water in the boiler through the medium of float valves and the piston operating within the cylinder being designed to control the supply of steam and water to the injector.

For a full description of the invention and the merits thereof and also to acquire a knowledge of the details of construction and the means for effecting the result, reference is to be had to the following description and accompanying drawings, in which:

Figure 1 is a diagrammatic view of a feed water regulating mechanism embodying the invention. Fig. 2 is an enlarged view of the cylinder and cylinder valve, a portion of the cylinder being shown in section. Fig. 3 is a detail view of the float valves arranged within the water column. Fig. 4 is a sectional view through the cylinder valve.

Corresponding and like parts are referred to in the following description and indicated in all the views of the drawings by the same reference characters.

The numeral 1 designates a water column which is designed to be applied to a boiler in the usual manner and communicates with the boiler through the lower water pipe 2 and the upper steam pipe 3. Leading from the water column 1 is a pair of steam pipes 4 and 5 having the admission of steam thereto automatically regulated through the medium of the valves 6 and 7 respectively. The

valve 6 is provided with an operating lever 8 having a float or buoyant member 9 applied thereto and the members are so arranged that the valve is closed when the water exerts a buoyant effect upon the said float, but is opened when the float falls due to a lowering of the water within the boiler. The valve 7 is also operated through a lever 10 having a float 11 pendent therefrom, the said parts being so designed as to open the valve when the water exerts a buoyant pressure upon the float 11 and to close the valve when the level of the water falls below the said float.

The steam pipes 4 and 5 lead to a valve 12 controlling the admission of steam to opposite ends of the cylinder 13 through the pipes 14 and 15. Operating within the cylinder 13 is a piston 16 having a piston rod 17 applied thereto and carrying an arm 18. The valve 12 is in the nature of a double three-way valve and is operated by means of a lever 19 which is connected to the arm 18 upon the piston rod through the medium of the connecting rod 20. The valve 12 is provided with a pair of exhaust ports 21 and operates to throw the rear end of the cylinder 13 alternately in communication with the steam pipe 4 and one of the exhausts, and the steam pipe 5 alternately in communication with the forward end of the cylinder and the opposite exhaust. The normal position of the piston 16 is at the rear end of the cylinder or that end opposite the cylinder head through which the piston rod passes as shown in Fig. 2, in which position the valve is moved to establish communication between the rear end of the cylinder and the steam pipe 4, the opposite end of the cylinder being in communication with an exhaust while the passage of steam through the steam pipe 5 is shut off.

An injector 22 which may be of any conventional construction is utilized for forcing the feed water into the boiler and communicates at one end with the steam pipe 23 and at opposite sides with the delivery pipe 24 and the water supply pipe 25. The steam supply pipe 23 is provided with a by-pass 26 where as the water supply pipe 25 is provided in a similar manner with the by-pass 27, the flow of steam through the former being regulated by the valve 28 while the flow of water through the latter is controlled by the valve 29. These two valves 28 and 29 are mounted upon a standard 30 connected to the for-

ward end of the cylinder 13 and are thereby held in a fixed position with relation to the cylinder. Each of the said valves is provided with an operating lever 31 connected 5 to a rod 32 attached to the piston rod 17. The portion of the steam supply pipe 23 between the two ends of the by-pass 26 is provided with a valve 33 and a valve 34 is applied to the water supply pipe 25 in a 10 similar manner, the said valves being both closed when the feed regulator is operating automatically and merely serving as a means whereby water can be fed into the boiler by manual means if desired. It will also be ob- 15 served that the by-pass 26 is provided with a valve 35 which is closed when the device is manually operated.

Describing the operation of the device it will be readily apparent that when the water 20 in the boiler falls below a predetermined level the float 9 will drop, thereby opening the valve 6 and admitting steam to the steam pipe 4. As previously mentioned the normal position of the piston 16 and the valve 12 25 is such that the rear end of the cylinder is in communication with the pipe 4, whereupon when the valve 6 is opened the steam will operate to move the piston 16 forwardly toward the front end of the cylinder. This 30 movement of the piston operates through the medium of the connecting rod 20 to reverse the position of the valve 12 so that the rear end of the cylinder is in communication with an exhaust while the forward end communi- 35 cates with the steam pipe 5. This forward movement of the piston also operates through the communicating rod 32 to open the two valves 28 and 29 whereby steam and water are simultaneously admitted to the injector 40 22 and the boiler is supplied with feed water through the delivery pipe 24. When the required amount has entered the boiler and the level of the water within the boiler has risen to such a height as to act upon the float 11, 45 the valve 7 is opened and steam is admitted to the steam pipe 5. This steam enters the forward end of the cylinder and moves the piston 16 to its original position, thereby closing the valves 28 and 29 and shutting off 50 the flow of feed water in the boiler, and re- 55 storing the valve 12 to its original position with the rear of the cylinder in communication with the steam pipe 4. It will thus be apparent that the supply of feed water to the boiler is entirely automatic and that the water within the boiler is positively pre- 60 vented from falling below a certain level or rising above a predetermined height. At the same time it will also be apparent that owing to the provision of the valves 33 and 34 the boiler can be supplied with feed water by manual means when desired.

Having thus described the invention, what is claimed as new is:

65 1. In a feed water regulator for boilers, the

combination of a cylinder, a piston operating within the cylinder, a double three-way valve for the cylinder, a pair of steam pipes leading from the double three way valve and having communication with the boiler, valves automatically regulating the admission of steam to the pipes; and means whereby the supply of feed water to the boiler is controlled by the piston. 70

2. In a device of the character described, 75 the combination of a water column, a cylinder, a piston operating within the cylinder, a cylinder valve, steam pipes leading from the water column to the cylinder valve, float valves for automatically regulating the admission of steam to the said steam pipes according to the level of the water within the water column, and means whereby the supply of feed water to the boiler is controlled by the piston. 80

3. In a device of the character described, 85 the combination of a water column, a cylinder, a piston operating within the cylinder, a cylinder valve, a pair of steam pipes leading from the water column to the cylinder valve, a float valve for one of the steam pipes whereby steam is admitted to the same when the water rises above a predetermined level, a float valve for the other steam pipe whereby steam is admitted to the same when the 90 water falls below a certain level, and means whereby the supply of feed water to the boiler is controlled by the piston. 95

4. In a device of the character described, 100 the combination of a water column, a cylinder, a piston operating within the cylinder, a double three-way valve communicating with opposite ends of the cylinder, means whereby the said double three-way valve is operated by the piston, a pair of steam pipes leading 105 from the water column to the three-way valve, each of said pipes being thrown alternately into communication with one end of the cylinder and an exhaust, means whereby the admission of steam to the said pipes is 110 automatically controlled by the height of water within the boiler, and means whereby the admission of feed water to the boiler is controlled by the piston. 115

5. In a feed water regulator for boilers, the 120 combination of an injector, a steam supply pipe leading to the injector and provided with a by-pass, a water supply pipe leading to the injector and also provided with a by-pass, a valve for each of the by-passes, a cylinder, a piston operating within the cylinder, connecting means between the piston and the before mentioned valves, for simultaneously operating the same, a cylinder valve, steam pipes leading from the cylinder valve and 125 having communication with the boiler, and valves for automatically regulating the admission of steam to the steam pipes. 130

6. In a feed water regulator for boilers, the combination of an injector, a steam supply

pipe leading to the injector, a water supply pipe leading to the injector, a valve for each of the pipes, a cylinder, a piston operating within the cylinder, connecting means between the piston and the before mentioned valves for simultaneously operating the same, a double three way valve for the cylinder, a pair of steam pipes leading from the double three way valve and having communication with the boiler, and valves automati-

cally regulating the admission of steam to the pipes according to the level of water within the boiler.

In testimony whereof I affix my signature in presence of two witnesses.
